UNITED STATES PATENT OFFICE

139,197

DESIGN FOR A COMBINED CONTAINER AND CLOSURE

Melvin H. Sidebotham, Newton, Mass.

Application February 10, 1943, Serial No. 109,518

Term of patent 14 years

(Cl. D58—8)

To all whom it may concern:

Be it known that I, Melvin H. Sidebotham, a citizen of the United States, residing at Newton, in the county of Middlesex, Commonwealth of Massachusetts, have invented a new, original, and ornamental Design for Combined Container and Closure, of which the following is a specification, reference being had to the accompanying drawing, forming part thereof.

In the drawing:

Fig. 1 is a plan view of a combined container and closure showing my new design.

Fig. 2 is a side elevational view.

I claim:

The ornamental design for a combined container and closure, as shown.

MELVIN H. SIDEBOTHAM.
